UNITED STATES PATENT OFFICE.

GALEN F. HIX, OF PORTLAND, MAINE.

CAR-DOOR SEAL.

Application filed January 27, 1922. Serial No. 532,120.

To all whom it may concern:

Be it known that I, GALEN F. Hix, a citizen of the United States, residing at Portland, in the county of Cumberland and 5 State of Maine, have invented new and useful Improvements in Car-Door Seals, of which the following is a specification.

This invention relates to seals for doors of freight cars. In devices of this character it is desirable, first that the device should be one which can be manufactured cheaply; second, that its nature be such that it can be easily applied to the hasp and staple of a freight car and freight car door; 15 and third that when so applied it will be impossible to remove the same from the hasp and staple without so damaging the car seal that it will be evident at a glance that the same has been tampered with.

20 The invention consists in a car door seal embodying the combination of elements set forth in the following specification and particularly pointed out in the claims.

Referring to the drawings:

25 Figure 1 is a plan view of a blank from which my improved car door seal may be constructed in a manner hereinafter set forth.

Fig. 2 is a side elevation of said blank.

30 Fig. 3 is a side elevation of said blank partly folded to form the lock.

Fig. 4 is a side elevation of said blank, still further folded to form the locking end thereof.

35 Fig. 5 is a sectional view of the finished car seal ready to be applied to the door.

Fig. 6 is a side elevation of the car door seal, partly in section, completed and in locked position.

40 Fig. 7 is a detail sectional view taken on line 7—7 of Fig. 6.

Fig. 8 is a side elevation partly in section similar to Fig. 6 but showing only one projection or tooth instead of two.

45 Like numerals refer to like parts throughout the several views of the drawings.

In the drawings, referring to Figs. 1 to 7 inclusive, 10 is a blank of sheet metal, the ends 11 and 12 of which are contracted or narrower than the intermediate or central portion 13. The end 11 is provided with a slot 14 and the end 12 is provided with two oppositely disposed projections 15 and 16, said projections being slightly out of alignment with each other longitudinally so that when folded the projection 16 may lie side by side with the projection 15. The

upper edges of said projections are inclined in opposite directions. A recess 17 is provided in the intermediate portion 13 of 60 the blank 10 on the face of said blank opposite to the face upon which the projections 15 and 16 are located.

Assuming the blank to be in the form illustrated in Figs. 1 and 2, the first process in forming the car seal from the blank is to fold the end 12 of said blank over approximately upon a line A, and thus produce the form illustrated in Fig. 3, the end 12 being formed as a U bend 18. The next 65 operation is to fold the U bend 18 backwardly in the direction of the arrow B to the form shown in Fig. 4, and finally the portion 13 of the blank is folded in the direction of the arrow C until it assumes the 70 75 position illustrated in Fig. 5.

It will be seen that the seal now consists, as shown in Fig. 5, of the end 11, the intermediate portion 13 and the end 12 folded so as to form a double U bend, viz, the inner 80 U bend 18 and the outer U bend 19 within which the inner U bend 18 is located.

To complete the car seal the opposite edges of the outer U bend are welded as 85 illustrated in Fig. 7 and in this finished form the recess 17 is brought directly into alignment with the free end 20 of the inner U bend 18. It will be seen that the edges of the projections 15 and 16 are inclined to each other and cross to form an acute angle 90 21 (see Figs. 5 and 6) and when applied to the car door the end 11 of the seal is inserted through the staple in the usual manner in order to lock the hasp thereto and said free end 11 is then inserted within the 95 inner U bend 18. The free end 11 is inserted within the inner U bend 18 by pushing said end 11 into the angle 21 between the oppositely inclined edges of the projections or teeth 15 and 16, whereupon the 100 free end 20 of the inner U bend 18 will be pushed downwardly into the recess 17 until the slot 14 arrives in alignment with the teeth 15 and 16, whereupon said teeth 15 and 16 will enter said slot.

105 It will be noted that the rear edges of the teeth 15 and 16 are practically at right angles with the inner face of the free end 20 of the inner U bend, so that it will be impossible to pull the end 11 out of said inner U bend, and it will be impossible to manipulate the inner U bend in such a manner as to release the end 11 from the teeth 15 and 16 without so damaging the

car seal that it will be obvious at a glance that it has been tampered with.

The device is used in the ordinary manner in which car seals are utilized and is attached to the car as hereinbefore described.

In Fig. 8 of the drawings a modified form of my invention is illustrated which is exactly the same as the form of my invention illustrated in Figs. 1 to 7 inclusive, except that a single tooth 15 is left and the tooth 16 is omitted.

Having thus described my invention, what I claim and desire by Letters Patent to secure is:

1. A car door seal comprising a strip of sheet metal provided with a slot adjacent to one end thereof and a double U bend at its opposite end, one of said U bends being located within the other, and a pair of oppositely disposed projections lying side by side on the inner side of the inner one of said U bends.

2. A car door seal comprising a strip of sheet metal provided with a slot adjacent to one end thereof and a double U bend at its opposite end, one of said U bends being located within the other and having one free end, and a pair of oppositely disposed teeth on the inside of the inner one of said U bends, the tops of said teeth being inclined toward said free end of said inner U bend and adapted to project into said slot when said end with the slot therein is inserted

within said inner U bend, whereby the two ends of said strip are locked together.

3. A car door seal comprising a strip of sheet metal provided with a slot adjacent to one end thereof and a double U bend at its opposite end, one of said U bends being located within the other and having one free end, and a projection on the inner face of one side of the inner one of said U bends, the outer one of said U bends having a recess therein adapted to receive said free end of the inner one of said U bends when the slotted end of said strip of metal is inserted within said inner U bend.

4. A car door seal comprising a strip of sheet metal provided with a slot adjacent to one end thereof and a double U bend at its opposite end, one of said U bends being located within the other and having a free end, and a pair of oppositely disposed projections on the inside of the inner one of said U bends, the outer one of said U bends having a recess therein adapted to receive said free end of the inner of said U bends when the slotted end of said strip of metal is inserted within said inner U bend.

In testimony whereof I have hereunto set my hand in presence of two subscribing witnesses.

GALEN F. HIX.
